CARD DISPLAY HOLDER

Robert Fisher, 51 Murphy St., South Yarra,
Victoria, Australia

Continuation of design application Ser. No. 82,770, Nov.
23, 1964. This application Oct. 22, 1965, Ser. No.
87,816

Claims priority, application Australia May 26, 1964

Term of patent 14 years

(Cl. D1—3)

FIG. 1

FIG. 2

FIG. 1 is a perspective view of the card display holder, the central part being broken away; and

FIG. 2 is a transverse sectional view of the card display holder shown in FIG. 1.

The dominant features of my design reside in the portion shown in full lines.

This is a continuation of design application Serial No. D.82,770, filed November 23, 1964, now abandoned.

I claim:

The ornamental design for a card display holder, substantially as shown and described.
